UNITED STATES PATENT OFFICE.

MAX R. LEHMAN, OF QUINCY, ILLINOIS, ASSIGNOR TO CASCADEN MANUFACTURING COMPANY, OF WATERLOO, IOWA, A CORPORATION.

DESIGN FOR A STOVE.

No. 37,667.

Specification for Design.

Patented Nov. 14, 1905.

Application filed August 24, 1905. Serial No. 275,678. Term of patent 14 years.

To all whom it may concern:

Be it known that I, MAX R. LEHMAN, a citizen of the United States, residing at Quincy, in the county of Adams and State of Illinois, have invented a new, original, and ornamental Design for Stoves, of which the following is a specification, reference being had to the accompanying drawing, forming part thereof.

The figure is a perspective view of a stove, showing my new design.

I claim—

The ornamental design for a stove, as shown.

MAX R. LEHMAN.
